CLAIM

The ornamental design for a rear support member for a cervical collar, as shown and described.

DESCRIPTION

FIG. 1 is a left front perspective view of a design of a support member for a cervical collar rear.

FIG. 2 is a right front perspective view of a design of a rear support member for a cervical collar.

FIG. 3 is a front view of a design of a rear support member for a cervical collar.

FIG. 4 is a rear view of a design of a rear support member for a cervical collar.

FIG. 5 is a left-side view of a design of a rear support member for a cervical collar.

FIG. 6 is a right-side view of a design of a rear support member for a cervical collar.

FIG. 7 is a top view of a design of a rear support member for a cervical collar, and,

FIG. 8 is a bottom view of a design of a rear support member for a cervical collar.

1 Claim, 4 Drawing Sheets
